ALMON J. PIERCE, OF BROOKLYN, NEW YORK, ASSIGNOR TO HYATT ROLLER BEARING COMPANY, OF HARRISON, NEW JERSEY, A CORPORATION OF NEW JERSEY.

SHEET-METAL CAP FOR JOURNAL-BOXES.

1,367,427.

Specification of Letters Patent.

Patented Feb. 1, 1921.

Application filed May 15, 1920. Serial No. 381,585.

To all whom it may concern:

Be it known that I, ALMON J. PIERCE, a citizen of the United States, residing at 192 Lincoln avenue, Brooklyn, county of Kings, 5 and State of New York, have invented certain new and useful Improvements in Sheet-Metal Caps for Journal-Boxes, fully described and represented in the following specification and the accompanying drawings, forming a part of the same.

The present invention relates to an improvement in journal-boxes, particularly those containing a set of anti-friction rolls to support a countershaft; and the object of 15 the invention is to furnish a cheap and effective closure for the end of the journal-box formed of a circular sheet-metal cap in place of the cast-metal cap which is ordinarily secured upon such boxes by means of 20 tap-bolts.

Where anti-friction rolls are employed, the bore of the box is materially larger than the diameter of the shaft supported therein, and the cap must necessarily close the 25 end of the chamber in which the rolls are supported.

The closure in the present invention consists of a plate of sheet-metal having a cylindrical flange bent laterally upon its periphery and adapted to crowd into the bore or chamber at the end of the journal-box. To receive the cap, the chamber has a uniform bore extended to its outer end, such bore being very cheaply formed in the manufacture of the boxes.

If desired, the periphery of the flange may be slightly expanded toward its margin, thus enabling it to enter the bore of the box more readily and to crowd more 40 firmly against the same when pressed wholly into the bore.

The margin of the flange is faced toward the end of the box, so that the plate may stand next to the roll-cage to form a wearing surface for the ends of the rolls or their cage within the box.

Where a cast-iron box is lined with sheet-steel to support the rolls, the periphery of the cap may be made of the same diameter 50 as the exterior of the lining so that a single bore is adapted to fit the lining and the cap.

The invention will be understood by reference to the annexed drawing, in which Figure 1 is a longitudinal central section of 55 a journal-box with the cap imperforate; Fig. 2 is a similar section showing the end

of the box with a cap having an aperture for the passage of the shaft; Fig. 3 is an elevation of the cap shown in Fig. 1 with a dotted circle indicating the periphery of the aperture for the passage of the shaft, as shown in Fig. 2; and Fig. 4 is an edge view of the cap.

a designates the body of the journal-box having a bore *b* forming a chamber to receive a lining *c* to sustain a set of anti-friction rolls *d*.

A head *f* is cast in one end of the box with bore *e* adapted for the passage of the shaft *g* from such journal-box to the opposite 70 bearing of a countershaft.

A set-screw collar *h* is shown secured upon the shaft in proximity to the head *f* to prevent end movement of the shaft.

It is customary to employ a cage to embrace and guide the rolls in a roller-bearing, and cage-heads *i* are shown within the ends of the lining, one of which heads revolves in proximity to the plate *k* of the cap, which thus restrains end movement of the rolls. 75

l designates the peripheral flange which is bent laterally from the plate *k* and forced into the end of the bore *b*. The length of the bore is made sufficiently greater than the length of the lining to admit the entire 85 width of the flange *l*, which when forced into the bore stands flush or even with the end of the box.

To stiffen the plate and furnish a seat for the application of pressure when forcing it 90 into the box, a web *m* is sloped from the plate *k* adjacent to and upon the same side as the flange *l*, and formed with a central boss *k'*.

In Fig. 1 this central boss is shown imperforate, so that the cap forms an absolutely oil-tight closure to one end of the box to retain the lubricant therein and exclude dust and dirt.

Such a tight joint is secured without any 100 labor or cost.

Where it is necessary to extend the shaft beyond both ends of the box, the middle portion of the boss *k'* is open for the passage of the shaft as shown in Fig. 2. This aperture is located where the dotted line *d* is shown upon the cap in Fig. 3.

In such case, the cap closes the space or chamber occupied by the rolls and thus prevents the intrusion of dirt, and the plate *k* of the cap forms a seat which restrains the movement of the cage and roll-set toward

that end of the box. The formation of this circular cap with a central boss gives it great stiffness and prevents any bending or deformity by accidental blows and the boss 5 sustains all the pressure required to force the cap into the bore.

A very great economy in the manufacture of journal-boxes is effected by the use of this pressed sheet-metal cap, as it is formed 10 by the single operation of stamping, and can be fitted to the same bore as the lining of the box; so that no preparation of the box is required to receive the cap.

Where the ordinary cast-metal caps are 15 applied to such boxes, the end of the box requires to be faced off, which is not necessary with the use of the sheet-metal cap.

The cast-metal cap also requires to be faced off to make an oil-tight joint with the 20 box, and is commonly attached thereto by tap-bolts which involves the drilling of the cap and the drilling and tapping of the box.

The cost of assembling and adjusting the parts of a cast-metal box to see if the bolts 25 are properly fitted, and the joint is tight between the box and cap, is necessarily eliminated by the present invention. The end of the box where the cap is secured by tap-bolts also requires facing off, which is not 30 necessary with the internally fitted caps; and the cost of producing the box by this single improvement is reduced twenty-five to thirty-five per cent.

The cap thus operates, whether or not the 35 shaft passes through it, to close that portion of the chamber in which the rolls rotate, thus protecting the rolls from dirt.

Where this invention is applied to journal-boxes on countershafts the boxes are necessarily 40 used in pairs, and all the end thrust can be sustained by screw-collars secured upon the countershaft against the outer ends of the boxes.

It is evident that the laterally bent flange 45 *l* is capable of springing or yielding more or less when pressed into the end of the box, and the flange thus enables the plate to exert a frictional grip upon the box, which could not be effected if a plain disk were 50 used and the edge of such disk crowded into the box.

The invention is shown herein applied to a roller-bearing having a lining in the box, and by making the peripheral flange of the 55 cap of the same size as the exterior of the lining the box can be made with a uniform bore throughout, thus saving the expense of making any special provision for fitting the cap to the box.

60 The caps shown herein are readily pressed into the end of the box in a few seconds by a "mandrel-press" or analogous means; the lining forming a stop to the inward movement of the cap.

For convenience, I have termed the peripheral flange of the cap a "cylindrical flange," which it would be to appearance even if expanded or tapered slightly to make it crowd into the box more readily.

It will be understood that the term "cylindrical" indicates the appearance of the cap and is used in this sense in the claims, and such language embraces a slight increase of diameter of the flange at its free edge.

The journal-box is not only reduced in 75 cost by my invention but is also reduced in size, which makes it more desirable for many purposes.

The invention is shown applied to a box having the body *a* made in one piece, but is 80 applicable to a box made in halves if the parts are tightly connected so as to hold the cap by a frictional engagement.

Solid rolls are shown in Fig. 1; tubular rolls on one side of Fig. 2, and spirally 85 wound rolls upon the opposite side of Fig. 2, the invention being applicable to a roller-bearing having any kind of cylindrical rolls.

Having thus set forth the nature of the invention what is claimed herein is:

1. A journal-box having a cylindrical chamber of uniform bore with a lining fitted therein, a set of anti-friction rolls fitted within the lining, and the end of the chamber closed by an elastic sheet-metal cap of 95 the same diameter as the exterior of the lining and forced into the chamber to the end of the said lining.

2. A journal-box having a cylindrical chamber of uniform bore extended to the 100 outer end of the box, a sheet-metal cap pressed into the end of the chamber, and a lining fitted to the remainder of the chamber, with a set of anti-friction rolls fitted inside the said lining.

3. A journal-box having a cylindrical chamber of uniform bore extended to the outer end of the box, a sheet-metal cap having a peripheral cylindrical flange adapted to crowd into the end of the chamber with 110 its edge turned outwardly, and a central boss extended outwardly within the said flange into line with the outer edge of the flange, to sustain the thrust of forcing it into the end of the journal-box.

4. A journal-box having a cylindrical chamber of uniform bore extended to the outer end of the box, a sheet-metal cap having a peripheral cylindrical flange adapted to crowd into the end of the chamber and having a sloped web adjacent to the peripheral flange extended flush with the outer edge of such flange and supporting a central boss to sustain the thrust of forcing the cap into the end of the journal-box.

In testimony whereof I have hereunto set my hand.

ALMON J. PIERCE.
